UNITED STATES PATENT OFFICE.

HERMAN H. BONEY, OF CHICAGO, ILLINOIS.

ELECTRIC-ARC LAMP.

1,083,658.

Specification of Letters Patent.

Patented Jan. 6, 1914.

Application filed September 20, 1911. Serial No. 650,416.

To all whom it may concern:

Be it known that I, HERMAN H. BONEY, a citizen of the United States, residing at the city of Chicago, county of Cook, and State 5 of Illinois, have invented certain new and useful Improvements in Electric-Arc Lamps, of which the following is a specification.

My invention relates to improvements in electric arc lamps, the object being to produce a lamp of this character which is capable of automatic adjustment to compensate for the burning of the carbons thereof, and to effect such adjustment by a simple and efficient mechanism.

15 A further object of my invention is to provide automatic means for replacement of the carbons of the lamp after the same have been burned out.

Other objects will appear hereinafter.

20 With these objects in view, my invention consists in the combinations and arrangements of parts hereinafter described and claimed.

My invention will be best understood by 25 reference to the accompanying drawings forming a part of this specification and in which,

Figure 1 is a side elevation of an electric arc lamp embodying my invention, Fig. 2 30 is a rear elevation showing mechanism for automatically feeding the adjustable carbon of the lamp, Figs. 3 and 4 are respectively side and front elevations of said mechanism, Fig. 5 is an enlarged vertical section taken 35 on line $x-x$ of Fig. 4, Fig. 6 is a vertical transverse section taken on line $y-y$ of Fig. 1, Fig. 7 is an enlarged horizontal section taken on line $z-z$ of Fig. 1, and Figs. 8 and 40 9 are views part in elevation and part in section, illustrating the mechanism for feeding carbons from the magazine into the carbon holder.

The preferred form of construction as 45 illustrated in the accompanying drawings comprises an adjustable carbon electrode 1 which is slidably mounted in a vertically movable carbon holder or tube 2, the latter having a flaring or bell-mouthed opening 3 at its upper extremity, as clearly illustrated in 50 Fig. 4. In Fig. 1 the lower or copper electrode is shown which is arranged in axial alignment with and directly below the carbon electrode 1. In order to control the automatic adjustability or feeding of the carbon electrode 1 during the burning of the lower end 55 thereof, a solenoid 5 is provided in which a

vertically movable core 6 directed by a guide 6' operates, as clearly indicated in Fig. 1. The elevated position of the core 6 is somewhat above the body of the solenoid 5 as 60 indicated by dotted lines, but the magnetism produced by the latter when energized draws said core downwardly. Extending downwardly from the core 6 and formed integral therewith is an axial stem 7 to the lower 65 end of which is pivoted an oscillatory lever 8 which is fulcrumed as at 9 to the main support or frame 10 of the lamp. The other end of the lever 8 or the end thereof opposite stem 7 is pivoted to a vertically extending rod 11 the upper end of which is pivoted to a bifurcated lug 12 carried by a vertically movable plate 13, the latter having a guide slot 13' formed therein. Within a stationary housing 13'' are mounted two 75 compression helical springs 14 and 15, the former acting on a vertically movable sleeve 16 passing through the lower end of the housing 13'' to retain the core 6 in an elevated position through the intervening connection, and the latter on a rod 17 which is also vertically movable. The sleeve 16 carries a curved horizontal bar 18 at its lower end to which is pivoted a vertically disposed link 18', the lower end of the latter being 80 pivoted to the free end of a clutch lever 19. The pointed or clutch end 19' of the clutch lever 19 is adapted to impinge the peripheral surface of the carbon electrode 1 when the sleeve 16 is moved upwardly against the 85 resistance of the spring 14. A rigid connection is formed between the sleeve 16 and plate 13 by means of a screw 20 reciprocating in a slot 20' formed in the housing 13'', and a second screw 21 secured in the housing 13'' cooperates with the slot 13' in guiding the plate 13 during the vertical reciprocations thereof. From this construction 90 it is seen that when the solenoid 5 is energized by the passage of an electric current 100 therethrough that the stem 7 will be moved downwardly and that the rod 11 will be pushed upwardly by the action of the lever 8. The first result of this action is to raise the sleeve 16 through the medium of the plate 13 and the screw 20 for effecting the oscillation of the lever 19 which thereupon 105 clutches the carbon electrode 1. Further upward movement of the rod 11 and sleeve 16 causes the tube 2 to move upwardly, the consequence being that a gap is formed between the electrodes for creating the arc 110

therebetween. The function of the spring 15 which acts upon an enlargement 15' formed on the rod 17 is to create a slight resistance to the upward movement of the tube 2 in order to assure that the clutching point 19' of the lever 19 will securely clutch the carbon and not slip thereon. After the carbon has been clutched the action of the solenoid 5 is such that the rod 11 will continue to move upwardly and also the sleeve 16 and tube 2 as aforesaid. An arm 2' projects laterally from the tube 2 and is formed integral with the rod 17, hence when said tube is moved upwardly the helical spring 15 is compressed, thus creating a resistance to said upward movement. Further resistance to the upward movement of the holder or tube 2 is caused by the spring 14 which acts upon the upper extremity of the sleeve 16, the latter being at this time in rigid connection with said tube through the medium of the link 18' and clutch lever 19. The holder 2 will continue to move upwardly for increasing the arc gap until the resistance of the springs 14 and 15 equals the force exerted by the solenoid 5. As the arc gap is increased, greater resistance is brought into the electric circuit and the strength of the solenoid thereby reduced, allowing the carbon electrodes to be lowered. However, the burning end of such carbon will be consumed faster than it is fed downwardly and when the arc gap is so increased by such burning that the pressure of the electric current is insufficient to maintain the arc, the electric circuit will be broken and the solenoid deenergized. The clutch 19 will now cease to act on the carbon electrode 1, whereupon the latter will fall into contact with the lower electrode 4, thus closing the circuit. Simultaneously with the closing of the circuit the solenoid 5 will resume its action on the parts connected therewith.

In order to adjust the helical springs 14 and 15 an adjusting screw 17' is provided at the upper end of the housing 13", the lower end of said screw abutting the upper ends of said springs. Extending laterally from the lower end of the housing 13" and formed integral therewith is a horizontal arm 18". This arm is provided with an opening in which the holder or tube 2 is adapted to reciprocate freely as shown in Fig. 4. Screwed into the extremity of the arm 18" is a vertical screw 20" having a head 20'" at the lower end thereof. Resting upon the head 20'" is a perforated lug 2', which extends laterally from the holder or tube 2 as shown in Fig. 4. In this manner the downward movement of the tube 2 is limited, any desired adjustment being effected by turning the head 20'".

From the foregoing description the general construction of the automatic feeding

mechanism controlling the carbon electrode 65 1 will be understood.

After the carbon electrode 1 has become burnt out, if no other means are provided, the remaining portion of the carbon will have to be removed by hand, but in this invention a magazine is supplied and so arranged as to feed the carbon therefrom automatically into operative position in case of the burning out of a preceding carbon. In this manner no appreciable interruption to the operation of the lamp during the life of the carbons is permitted. The magazine 22 containing the carbons is arranged somewhat above the flaring mouth 3 and the construction of the same is such that when the top of the carbon electrode 1 within the tube or holder 2 is below the level of the mouth 3, the next carbon electrode will be pushed automatically into position thereabove or in alinement with the carbon electrode 1. This magazine and the automatic means for replacing the carbons will be described hereinafter.

The frame 10 is mounted upon a stud 23 formed integrally with a base 24 in such a manner as to be angularly adjustable thereon, there being a stud screw 25 for effecting any desired adjustment. A reflector 26 is provided and mounted adjacent the lamp as shown in Fig. 1. In order to render the lamp vertically adjustable to bring the arc of the lamp in the same horizontal plane as the focus of the reflector 26 a set screw 27 and a lock nut 28 is provided, said set-screw acting upon the top of the stud 23 as clearly shown in Figs. 1 and 6.

The magazine 22 is vertically disposed and L-shaped in cross section, the lower end of one of the sides thereof being secured to a pair of laterally extending lugs 29 formed integral with the housing 13". These lugs are screwed to the magazine as shown in Fig. 4, and interposed between the same and the side of the magazine are circular insulating blocks 30, whereby said magazine is electrically separated from the carbon feeding mechanism. The housing 13" is held rigidly in position by means of the upwardly extending curved arm of the frame 10 as shown in Figs. 1 and 4, said arm being formed integral or soldered to said housing. Since the magazine 22 is rigidly secured to the housing 13" this also is stationary and immovable.

The carbons 1 are arranged in the magazine 22 as shown in Fig. 1, there being a leaf spring 31 secured to one side of the magazine and serving to push the carbons into operative position when released by the mechanism to be presently described. The carbons 1 are retained in the magazine by means of a latch 32 which is supported by arms 33 and 34 as shown in Figs. 2 and 3.

The latch 32 is secured in locked position by means of a thumb screw 35 which is tapped into one side of the magazine as shown in Fig. 4. A vertically movable carbon retaining member 36 is provided at the upper end of the magazine 22 and is supported by a vertically movable rod 37 which is slidably mounted in a cylinder 38. At the lower end of the rod 37 a small piston 39 is provided which is adapted to reciprocate freely in the cylinder 38, there being a helical compression spring 40 interposed between said piston and the upper end of the cylinder 38 for creating a resistance to the upward movement of the rod 37 and the retaining member 36, the lower edge of the latter being beveled as shown in Fig. 3. The retaining member 36 normally remains at its lowest terminal of movement and the upper end of the lowermost carbon in the magazine 22 rests against it. When such lowermost carbon 1 is fed into the carbon holder 2 it is moved from its full line position, in Fig. 8, through its dotted line position 1' in Fig. 8 and its full line position in Fig. 9, passing under the retaining member 36 and to a vertical position indicated by dotted lines 1'', then dropping into the carbon holder 2. Should there be a carbon 1 in the holder 2 with its top end substantially in the position indicated in Fig. 9 and the solenoid 5 be energized during the movement of the lowermost carbon 1 from the magazine 22, such carbon would be forced upwardly to a position, such as indicated by the dotted lines 1''' in Fig. 9 raising the member 36 and compressing the spring 40. As soon as such carbon is moved downwardly or outwardly the spring 40 will return the member 36 to its normal position. The carbons 1 contained in the magazine 22 are preferably insulated from the carbon feeding mechanism and held in inoperative position by means of a vertically movable releasing catch 41 which is formed preferably of insulating material such as fiber, vulcanite or the like. The releasing catch 41 is adapted to slide vertically between two lugs 42 which depend from a carbon chute 43 curved in cross section and in which the points of the carbons rest. The upper end of the releasing catch 41 projects into the chutes 43 and normally abuts the lowest carbon contained within the magazine thus retaining all of the carbons contained therein. The catch 41 is mounted at the upper extremity of a threaded rod 44 which is screwed into the curved bar 18 and adjustably secured therein by means of a locking nut 45. The construction is such that when the solenoid 5 is energized and the bar 18 consequently moved to its elevated position that the point of the catch 41 will abut the lowest carbon within the magazine 22 and thus retain the carbons therein. But when the solenoid 5 is deenergized long enough for the dash pot 50', through its connecting mechanism, to allow catch 41 to fall to its position indicated in Fig. 9, the lowest carbon within the magazine will be moved laterally and downwardly into the holder 2 by its own weight, if the carbon within the tube 2 has become burnt out or the upper end thereof depressed below the level of the chute 43. While the upper end of a carbon 1 in the holder 2 extends above the chute 43, it prevents a new carbon from being fed into said holder 2 regardless of the position of catch 41. The arc lamp is so designed that while in use the upper end of the catch 41 will reciprocate substantially between its full line position and its dotted line position 41', in Fig. 8, and when the lamp is not in use, the catch 41 will be lowered to its position indicated in Fig. 9. The dash pot 50' preventing, by means of its connecting mechanism, the catch 41 from being lowered to its position indicated in Fig. 9, until solenoid 5 has been deenergized long enough for such action to take place. This retarding effect of the dash-pot 50' causes the catch 41 to be maintained in and between its positions indicated in Fig. 8, while the lamp is in use, and the carbon is being fed downwardly into the holder 2 as it is consumed.

It is apparent that the solenoid 5 is arranged in the lamp circuit, a wire extending from the solenoid to the arm of the lamp support 10, thence through the carbon regulating mechanism, thence across the arc gap, and thence through the lower carbon holder 100 to the other side of the circuit. The lower electrode holder comprises a bracket 46 secured to the support or frame 10 and insulated therefrom by means of a block 47. To the upper end of the bracket 46 is pivoted a bell-crank lever 48 one end of which embraces the electrode 4 and the other an edge of a vertically movable locking wedge 49 which is illustrated in detail in Fig. 7. The lower end of the wedge 49 is provided with an adjusting screw 50 for regulating the height of the electrode 4. In order to insert the electrode 4 the wedge 49 is moved upwardly a short distance which forms a sufficient clearance therebetween and the bracket 46 for the electrode. After placing the latter the wedge 49 will fall into the position shown in Fig. 1, thus locking the electrode in position. It is clear from this construction that a good electric contact is made, since not only does the bell-crank 48 engage the electrode 4 but one edge of the wedge 49. When the screw 50 is properly adjusted to suit the diameter of the electrode 4, satisfactory results are obtained. In order to retard the action of the stem 7 depending from the core 6 a dash-pot or cylinder 50' is provided, there being a piston 51 operating in

said dash-pot as illustrated by dotted lines in Fig. 1. The piston rod 52 connects the piston 51 with a projecting portion of the frame 10 whereby said piston is held in a stationary position. The piston 51 is so fitted in the dash-pot 50 that movement in either direction of the latter therein is resisted by atmospheric pressure.

Operation of the lamp is as follows: After 10 the lower end of the carbon electrode 1 has become burnt away sufficiently to produce a gap between itself and the electrode 4 to prevent the passage of a current, then the solenoid 5 ceases to act, the same being deenergized. The clutch 19 will then no longer hold the carbon in position and automatically releases the same, whereupon the falling of the latter will renew contact with the electrode 4. A current will again be established 20 for effecting the normal action of the solenoid 5 and the clutch 19 controlled thereby. This alternate action will continue during the life of the first carbon, whereupon the lowest carbon within the magazine will automatically fall into position above the burnt out carbon as hereinbefore described.

An electric arc lamp of the construction set forth is simple of construction and efficient in operation. Moreover, since the 30 lamp is provided with a carbon magazine capable of containing a plurality of carbons, the lamp will operate over an extended period without any attention.

While I have illustrated and described the 35 preferred construction for carrying my invention into effect, this is capable of variation or modification without departing from the spirit of the invention. I therefore do not wish to be limited to the exact details 40 of construction set forth but wish to avail myself of such variations and modifications as come within the scope of the appended claims.

Having described my invention what I 45 claim as new and desire to secure by Letters Patent is:

1. An electric arc lamp comprising a frame, a solenoid secured to said frame so that the axis thereof is vertically disposed, a 50 core operating within said solenoid and adapted to be drawn downwardly when the latter is energized, an axial stem formed integral with said core and depending therefrom, a dash-pot and piston arranged in connection with said stem and adapted to retard the movement thereof in either direction, a lever fulcrumed to said frame and pivoted at one end to said stem, a vertically disposed rod pivoted to the other end of 55 said lever and extending upwardly therefrom, a spring housing arranged adjacent the upper end of said rod, a vertically disposed compression helical spring contained within said housing, there being a longitudinal slot formed in one side of the latter, a

vertically movable plate pivoted to the upper end of said rod and mounted to move vertically on the side of said housing in which said slot is provided, a screw secured in said plate and extending through said slot into said housing, a vertically movable sleeve arranged axially in said housing into which said screw is passed, said compression spring abutting the upper end of said sleeve and adapted to resist the upward movement thereof, a vertically disposed tubular carbon holder arranged adjacent said sleeve, a clutch lever projecting into said carbon holder the free end of which extends horizontally therefrom, a link connecting the free end of said clutch lever with the lower end of said sleeve and adapted to render said clutch lever operative upon an upward movement of the latter, a carbon contained within said carbon holder and adapted to be secured therein by the operation of said clutch lever, said carbon forming an electrode, a second electrode arranged beneath said carbon electrode and adapted to contact therewith upon release of said carbon electrode upon the downward movement of said link, and means for regulating the tension of said helical spring, substantially as described.

2. An electric arc lamp comprising a frame, a vertically disposed solenoid secured to said frame, a core operating in said solenoid and adapted to be drawn downwardly when the latter is energized, a stem depending from said core and adapted to operate therewith, an oscillatory lever fulcrumed to said frame and pivoted at one end to said stem, a vertical rod pivoted to the other end of said lever and extending vertically therefrom, a slotted plate pivoted to the upper end of said rod, a vertically disposed housing, a screw projecting from said housing and passing through the slot of said plate forming a guide for the movement thereof, a screw rigidly secured in said plate and projecting into said housing, there being a slot formed in one side of the latter to permit of the free vertical movement of said last named screw, a vertical sleeve adapted to reciprocate in said housing into which said last named screw is passed forming a rigid connection, a vertical rod adapted to move freely in said sleeve and projecting upwardly therefrom into said housing, a helical spring surrounding said last named rod and adapted to exert a downward pressure thereon, a second helical spring surrounding said last named rod and said first named helical spring, said second helical spring being adapted to exert a downward pressure on said sleeve, an adjustable nut threaded into the upper end of said housing abutting the upper end of both of said springs, said last named rod projecting through the lower end of said sleeve, a tubular carbon holder

- formed integral with said last named rod and adapted to move vertically therewith, a bar into which the lower end of said sleeve is threaded, a link depending from said bar and 5 pivoted thereto, a clutch lever pivoted to one side of said carbon holder and having a clutching point projecting therein, the free end of said clutch lever being pivoted to the lower end of said link, the construction 10 being such that when said link is elevated that said clutching point will be rendered operative, a carbon forming an electrode and loosely mounted in said carbon holder and adapted to be clutched therein upon the upward movement of said first named rod, the latter movement being effected upon the energizing of said solenoid, a second electrode arranged in axial alinement with said carbon electrode and vertically under the 15 same, said electrodes being adapted to be spaced apart forming an arc gap when said solenoid is energized, and means for limiting the downward movement of said carbon holder substantially as described.
- 20 3. In an arc lamp, the combination with a base, of a supporting arm mounted thereon; a casing carried by said arm; a carbon holder mounted on said casing by means permitting rectilinear reciprocatory movement; a sleeve having one end slidably mounted in said casing; a rod carried by said carbon holder, slidably mounted in said sleeve and extended through said casing; compression springs in said casing pressing 25 downwardly on said rod and said sleeve; a clutch dog projecting into said carbon holder and operatively connected with said sleeve; and means for automatically raising said sleeve for engaging said clutch dog with the carbon electrode in said carbon holder and elevating the same.
- 30 4. In an arc lamp, the combination with a base, of a supporting arm thereon; a casing rigidly secured to said supporting arm; a 35 sleeve having one end mounted for reciprocation in said casing; a rod extending through said casing and said sleeve and
- slidably mounted therein; a carbon holder mounted on said casing by means permitting rectilinear movement and provided 50 with an arm secured to the lower end of said rod; a clutch dog pivoted on said carbon holder and projecting thereinto; means operatively connecting said clutch dog with said sleeve; and means for imparting reciprocatory movement to said sleeve.
- 55 5. In an arc lamp, the combination with a support, of a casing rigidly mounted thereon; a sleeve having one end mounted for reciprocation in said casing; a rod extending 60 through said sleeve and casing and slidably mounted therein; springs in said casing pressing downwardly on said sleeve and said rod; a carbon electrode holder carried by said rod; a clutch dog pivotally mounted on 65 said holder; a connection between said sleeve and said clutch whereby said clutch is forced into said holder for engagement with the carbon electrode mounted therein upon the upward movement of said sleeve; a plate 70 mounted for reciprocation upon said casing; a connection between said sleeve and said plate; and a common source of power whereby said plate may be reciprocated, imparting a similar motion to said sleeve. 75
6. In an arc lamp, the combination with a carbon holder having automatic feeding means for feeding carbons therethrough, of a magazine located adjacent said carbon holder; a chute extending from said magazine to said holder; a catch carried by said automatic feeding means and adapted to have its upper end extended into said chute while the arc lamp is in use; and an upwardly yielding carbon retainer carried by 80 and spanning the open upper portion of said magazine. 85

In witness whereof I have signed my name to this specification in the presence of two subscribing witnesses.
